UNITED STATES PATENT OFFICE

129,372

DESIGN FOR A TEXTILE FABRIC

Curt E. Forstmann, Montclair, N. J.

Application June 13, 1940, Serial No. 92,972

Term of patent 3½ years

To all whom it may concern:

Be it known that I, Curt E. Forstmann, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

In the drawing, the sole figure is a plan view of a portion of the fabric illustrating the subject design in which the broken lines *a*, *b* designate adjacent narrow diagonal stripes.

The design comprises a fabric having relatively faint narrow diagonal stripes composed of short loops arranged in the general direction of the stripes, said stripes being separated by series of longer loops arranged at substantially right angles to said narrow stripes.

I claim:

The ornamental design for a textile fabric, as shown and described.

CURT E. FORSTMANN.
